(57) **CLAIM**

We claim the ornamental design for a cigarette carton assembly, as shown and described.

DESCRIPTION

FIG. 1 is a front, bottom, left side perspective view of a first embodiment of a cigarette carton assembly consisting of a non-transparent material containing packages of smoking articles showing our new design.

FIG. 2 is a rear elevation view thereof, the front elevation view being an identical mirror image thereof.

FIG. 3 is a right side elevation view thereof, the left side elevation view being a mirror image thereof.

FIG. 4 is a top plan view thereof.

FIG. 5 is a front, bottom, left side perspective view of a second embodiment of a cigarette carton assembly consisting of a transparent material containing packages of smoking articles showing our new design.

FIG. 6 is a rear elevation view thereof, the front elevation view being an identical mirror image thereof.

FIG. 7 is a right side elevation view thereof, the left side elevation view being a mirror image thereof; and,

FIG. 8 is a top plan view thereof.

The ornamental design which is claimed is shown in solid lines in the drawings. Any shading lines or broken lines in the drawings are for illustrative purposes only and form no part of the claimed design.
